UNITED STATES PATENT OFFICE

129,966

DESIGN FOR A SMOKING PIPE AND THE LIKE

Joseph J. Kolar, Wheaton, Ill., assignor to Irving
H. Fishlove, Chicago, Ill.

Application August 23, 1941, Serial No. 103,002

Term of patent 7 years

To all whom it may concern:

Be it known that I, Joseph J. Kolar, a citizen of the United States, residing at Wheaton, in the county of Du Page and State of Illinois, have invented a new, original, and ornamental Design for Smoking Pipes and the like, of which the following is a specification, reference being had to the accompanying drawing, forming part thereof.

Fig. 1 is a side elevational view of a smoking pipe showing my new design.

Fig. 2 is a top plan view of same.

The dominant features of my design reside in the portions shown in full lines in the drawing.

I claim:

The ornamental design for a smoking pipe and the like, as shown and described.

JOSEPH J. KOLAR.
